(57) CLAIM

The ornamental design for a combined reusable toiletseat cover and storage case, as shown and described.

DESCRIPTION

FIG. 1 is a top plan view of a combined reusable toiletseat cover and storage case showing my new design;

FIG. 2 is a bottom plan view thereof;

FIG. 3 is a side elevational view thereof;

FIG. 4 is a rear elevational view thereof; and,

FIG. 5 is a front elevational view thereof.

The broken line showing of indicia is for illustrative purposes only and forms no part of the claimed design.
